ELECTRIC SHOE POLISHING MACHINE WITH RECIPROCATING POLISHING BELT

George T. Fielding, Stamford, Conn.

Application August 22, 1945, Serial No. 611,954

3 Claims. (Cl. 15—97)

1

This invention relates to a shoe polishing machine. While machines of this class have been known to the art for many years, there has never been contributed a simple, small, inexpensive and compact mechanism that is adapted for effective trouble free operation. My invention contributes a machine of this class that will yield results long sought in this art.

One feature of my machine resides in the utilization of a drive assembly or actuating mechanism that is adapted for movement by the shoe that is applied to the polishing cloth of the machine. The pressure of the shoe against the polishing cloth may thus be easily controlled by the person whose shoe is being polished, it being preferred that the drive assembly move against the resistance of a spring as well as gravity. As a further feature of this part of the invention the drive assembly is preferably pivoted, and is moved about its pivot by the pressure of the shoe against the polishing cloth that is actuated by the drive assembly.

As a further feature of the invention, the polishing cloth is actuated by eccentric means secured to the ends of the cloth. Preferably, the ends of the cloth are secured to eccentric means rotating about the same axis, and with the ends of the cloth preferably secured to the eccentric means substantially 180° apart relatively to the axis of rotation. Through this arrangement, the cloth is reciprocated and moved longitudinally relatively to the axis of rotation of the eccentric means. This imparts a criss-cross action to the cloth as well as a reciprocation thereof, and contributes an extremely desirable polish.

A further feature of the invention resides in the utilization of disks for reciprocating the polishing cloth, the disks being mounted for rotation about one axis with the ends of the polishing cloth secured thereto as generally set forth above. The disks serve to protect the cloth against abrasion and against destruction such as would be probable with another type of operating means.

As a further feature of the invention, the polishing cloth is held in a bight relatively to the machine for the insertion of a shoe into polishing relation thereto. As still a further feature of this part of the invention, the polishing cloth is held in an inverted bight relatively to the top of a casing with the ends of the cloth passing through slots in the casing for actuating means in the casing.

A further feature of the invention resides in the utilization of a yielding shoe support on

2

which the shoe to be polished is placed, the movement of the shoe support, or foot treadle, as it may be called, acting automatically to start the operation of the motor of the machine.

Other features of the invention reside in the means securing the polishing cloth so that it may be readily replaceable, in the utilization of vacuum cups to support the casing, and particular structural details to be described hereinafter.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized by those skilled in the art as a basis for the designing of other structures for carrying out the several purposes of my invention. It is important, therefore, that the claims to be granted me shall be of sufficient breadth to prevent the appropriation of my invention by those skilled in the art.

Referring now to the drawings, Fig. 1 is a perspective view of the machine of my invention. Fig. 2 is a vertical view of the machine with the side of the casing removed to illustrate the parts thereof. Fig. 3 is an enlarged view of the securing means for one end of the polishing cloth, illustrating the operation thereof. Fig. 4 is a section along the lines 4—4 of Fig. 2.

Referring now more particularly to the drawings, reference numeral 10 indicates a casing relatively to which my invention may be associated. This casing may be manufactured in any suitable way, and its method of construction is not an important feature and will, therefore, not be described in detail here. The upper surface of the box-like casing 10 is formed with a pair of slots 11 extending vertically downwardly into the casing. A polishing cloth 12 is adapted to be held so as to form an inverted bight at its center, and with portions of the cloth extending through the slots 11 into the box-like casing 10. For holding the polishing cloth in an inverted bight, there is secured to the casing 10 a standard 13. A pair of springs 14 are secured at 15 to the standard 13 and extend downwardly toward the cloth, being secured to the polishing cloth 12 by means of rings 16 and cloth loops 17 stitched to the polishing cloth as at 18. It is, of course, obvious that the polishing

3

cloth 12 will be held yieldingly in its inverted bight, and that it will be possible to move the cloth at will against the resistance of the relatively light springs 14.

To the bottom of casing 10 there is secured one leaf 19 of a hinge 20, the other leaf 21 being secured to a mounting plate 22 whereby the said mounting plate may pivot relatively to the casing 10. A pair of springs 23 rest between the mounting plate 22 and the bottom 24 of the casing for cushioning the plate, the springs being housed in shallow depressions 25 of the said bottom 24. A spring 26 is mounted about a headed pin 27 that is in guide relation to the plate 22, extending through a bore 22a in the said plate. Spring 26 presses against mounting plate 22 and tends to urge it to its position of Fig. 2, the mounting plate 22 being movable against the pressure of spring 26 and about its hinge 20 as will hereinafter be set forth. Pin 27 is preferably secured to the bottom 24 of casing 10 by threading it into the position illustrated best in Fig. 2.

Secured to the mounting plate 22 is the standard 28 of a drive assembly comprising an electric motor 29 and a reduction gear housing 30 within which there is contained the usual reduction gears operated by the motor 29 for rotating an actuating shaft 31. It will be appreciated that the motor 29 together with gear housing 30 and shaft 31 will be rotatable as a unit with standard 28 on mounting plate 22 and about the pivot of hinge 20.

Secured to the shaft 31 are a pair of disks 32, there being one disk for each end of the shaft. To each disk 32 there is secured a cloth fastener 33, the construction of which is best illustrated in Fig. 3. Each cloth fastener 33 is pivotally and rotatably assembled to one of the disks by a screw 34 extending into a threaded bore of the disk, and is kept spaced from its disk by a washer 35. Each end of the polishing cloth 12 is formed with a loop 36 as best seen in Fig. 3 whereby to slip over an arm 37 that is formed as a part of each cloth fastener 33. Because of the nature of its construction, each arm 37 may be moved to open a space 38 for the ready removal or insertion of the loops 36 of polishing cloth 12. A retainer loop 39 is pivoted at 40 to each of the fasteners 33, and is adapted to move from the position of Fig. 3 into the position of Fig. 2 for holding the arm 37 in position to close the opening 38, and thereby maintain the polishing cloth 12 assembled to the cloth fastener 33. It, undoubtedly, is quite apparent at this time that the polishing cloth may readily be secured to the fasteners 33 and the disks 32, and readily removed for cleaning or renewal as the case may be.

It should be emphasized here that the disks 32 serve to actuate the polishing cloth as would mere eccentric arms, but the disks protect the polishing cloth so that it is not subjected to the same hazards as when actuated by arms, cranks, or the like.

For controlling the rotation of the electric motor 29 I utilized a push switch designated generally by reference numeral 45 and comprising a stationary contact 46 and a movable button 47. The button 47 is adapted for depression by a foot treadle 48 against the pressure of a spring 49. The spring 49 normally maintains the foot treadle 48 in its position of Fig. 2, with a screw 50 serving as a limit member. The treadle 48 is secured by a pair of screws 51 to the upper surface of the box-like casing 10, and has sufficient resiliency to flex from the position of Fig.

5 2 downwardly against the surface 52 of the casing 10 so as to move the push button 47 into contact relation to stationary contact 46. This, of course, excites the motor 29.

It will be interesting to note that the two cloth fasteners 33 are positioned substantially 180° apart relatively to the axis of actuating shaft 31. In this way, the ends of the cloth will not only be reciprocated a distance equal substantially to the diameter of each disk 32, but will be moved longitudinally a similar distance. This means that the polishing cloth will have not only a reciprocating action but also a criss-cross action so as to impart excellent polish to a shoe. It will further be appreciated that the springs 14 will at all times maintain the polishing cloth 12 to form an inverted bight for a shoe that is applied to the treadle 48. In this way, a firm and positive movement may be imparted to the cloth 12, while allowing for the formation of the bight for the entry of a shoe. It will also be appreciated that the mere application of the shoe to the bight will effect a depression of treadle 48 so as to begin the operation of the motor 29.

25 For further protecting the cloth, the operating parts of the machine may be shielded by a sheet metal member 54 best seen in Fig. 4, but shown in outline in Fig. 2.

30 Those skilled in the art will further appreciate that in order to apply more pressure between the shoe and the polishing cloth, it will be necessary only to apply more pressure by the shoe against the cloth so as to rotate the drive assembly about hinge 20 against the resistance of spring 26.

35 For securely maintaining the casing of my invention against vibration relatively to the floor, I prefer to equip the casing with a series of vacuum cups 55, these vacuum cups functioning to hold the casing firmly in operating position, the pressure of the foot and any vibration of the machine acting to increase the effectiveness of the vacuum cups.

40 I believe that the object of my invention and the operation thereof should be apparent to those skilled in the art.

I now claim:

45 1. In a combination of the class described, a box-like casing, a foot treadle mounted on the top of said box-like casing and adapted for slight depression relatively to said casing as by a foot applied thereto, a polishing cloth, resilient means extending between said casing and cloth for yieldingly holding the cloth in an inverted bight over said foot treadle with the ends of the cloth entering the box-like casing through slots formed in said casing at each side of said treadle, an electric motor within said casing, a drive shaft rotatable by said motor, an eccentric at each end of the 50 said shaft with said eccentrics positioned 180° apart relatively to the axis of said shaft, means securing the ends of said cloth to said eccentrics for reciprocation thereby, and means pivotally mounting said motor and drive shaft for movement as a unit relatively to said casing on an axis parallel to said drive shaft whereby said motor is moved on said pivotal mounting as by the pressure of a shoe applied against the bight of said cloth.

55 2. In a combination of the class described, a casing, a shoe support on the top of said casing, a polishing cloth, resilient means extending between said casing and cloth for yieldingly holding the cloth in an inverted bight over said shoe support with the ends of the cloth entering the cas-

ing through slots formed in said casing at each side of said shoe support, an electric motor, a drive shaft rotatable by said motor, means integrally movable with said motor for mounting said drive shaft for rotation, means pivoting said motor and shaft as a unit within said casing on an axis parallel to said shaft, an eccentric at each end of said shaft with said eccentric positioned 180° apart relatively to the axis of said shaft, and means securing the ends of said polishing cloth to the said eccentric whereby the ends of said cloth are rotated with the eccentric and the cloth is reciprocated.

3. In a combination of the class described, a casing, a shoe support carried by said casing, a 15 polishing cloth, resilient means extending between said casing and cloth for yieldingly holding the cloth in an inverted bight over said shoe support with the ends of the cloth extending downwardly at each side of said shoe support, an electric motor, a drive shaft rotatable by said motor, means integrally movable with said motor for mounting said drive shaft for rotation, means pivoting said motor and shaft as a unit to said casing below said shoe support for movement relatively to said casing on an axis parallel to said 20 drive shaft, an eccentric at each end of said shaft

with said eccentric positioned 180° apart relatively to the axis of said shaft, and means securing the ends of said polishing cloth to the said eccentric whereby the ends of said cloth are rotated with the eccentric and the cloth is reciprocated.
